UNITED STATES PATENT OFFICE.

FRANCES M. NEWMAN, OF WHITEAGLE, OKLAHOMA.

TIE SPACER.

Application filed June 8, 1926. Serial No. 114,516.

This invention relates to tie spacers such as are used on railways for the purpose of properly spacing the ties after they have become bunched together under the action of 5 trains passing over the road and the general object of the invention is to provide a very effective spacing means of this character which embodies a rail anchor, a tie engaging member, and a lever so engaged with 10 the anchor and the tie engaging member that as the lever is oscillated in one direction the anchor will hold on the rail and the tie will be drawn forward and as the lever is drawn in the opposite direction the tie 15 will act as a base of support and the anchor will be forced forward, thus securing a step by step action of the tie spacer to shift the tie from its original position to its predetermined position.

20 A further object is to provide a mechanism of this character which is simple, easily operated, and whereby ties may be shifted without the aid of railway jacks.

25 My invention is illustrated in the accompanying drawings wherein:—

Figure 1 is a top plan view of a tie spacer constructed in accordance with my invention;

Fig. 2 is a longitudinal sectional view 30 thereof; the rail being in elevation;

Fig. 3 is a section on the line 3—3 of Figure 1;

Figure 4 is a section on the line 4—4 of Figure 2.

35 Referring to these drawings A designates the usual rail and adapted to be mounted upon this rail and engage the head thereof is the anchor 10. This anchor is formed to provide two downwardly extending lugs 11 40 which embrace the head of the rail and lock upon the head of the rail when the anchor is angularly shifted to thus hold the anchor from any further movement. This anchor 10 at one end has the downwardly depressed 45 extension 12 and at the other has an aperture for a bolt 13.

Adapted to engage with the tie B which is to be moved, is a shoe 14 which is reenforced upon its upper face by web 15 and 50 has a lug 16 which extends down or hooks behind the tie. This shoe 14 has pivotally mounted upon it a lever 17 fulcrumed at 18 to the shoe and pivotally attached to this lever is the link 19 which in turn is fulcrumed at 20 to the anchor extension 12. Also engaged on the shoe 14 is the cross piece

21 which is apertured for the passage of the bolt 13 and extends over the head of the rail. A coiled compression spring 22 surrounds the bolt 13 and bears at its ends against 60 the anchor 10 and the cross piece 21 as shown. Integral with the cross piece 21 and the shoe 14 is a runner 23 which rests upon the ties at the side of the rail.

In the operation of this mechanism the 65 operator places his foot and, therefore, his weight upon the shoe 14 adjacent the tie B and thus holds the lug 16 firmly engaged behind the tie. If now the lever 17 be drawn toward the operator, the link 19 will 70 act to cramp the anchor 10 and jam it on the rail A and a further movement of the lever 17 will shift the shoe 14 forward drawing the tie B forward. This forward movement will also be transmitted to the cross 75 piece 21 and to the runner 23. When a full stroke of the lever 17 has been secured and it is necessary to shift the tie still further, the movement of the lever 17 is reversed. This will cause the forward movement of 80 the link 19 and the adjacent end of the anchor 10 will be also moved forward. If it were not for the spring 22 the anchor 10 would again cramp upon the rail head but the spring 22 will urge one end of the anchor 10 forward at the same time that the other end of the anchor 10 is urged forward 85 by means of the advancing link 19. When the anchor has been advanced a suitable degree, the movement of the lever is again reversed which will act, as previously described, to draw the tie B again forward. Thus, it will be seen that by oscillating the lever 17 a step by step movement is given to 90 the tie.

95 My improved tie spacer affords an exceedingly economical tool for spacing ties under rails. It does away with the need of excavating beneath the tie, it moves the tie without damaging the latter and is a time saver 100 and will work past any make of rail joint without interruption and operates on either side of the track.

I claim:—

1. A tie spacer of the character described comprising a rail anchor consisting of a bar having means thereon to embrace the head of the rail and bind thereon when the anchor is angularly shifted upon the rail, a shoe adapted to rest upon 105 ties and having means for engaging behind a tie, the bar constituting the anchor ex-

tending approximately at right angles to the shoe, a lever pivoted upon the shoe and operatively connected with one end of the rail anchor whereby as said lever is shifted 5 in one direction the shoe will be drawn toward the anchor and as the lever is shifted in the other direction one end of the anchor will be forced away from the shoe, a transverse bar carried by the shoe adapted to 10 extend across a rail approximately parallel to the anchor carrying bar, and a spring engaging the ends of said bars remote from the shoe and urging them away from each other.

15 2. A tie spacer of the character described comprising a rail anchor having means embracing the head of the rail, the rail anchor binding upon the rail when it is angularly shifted, a shoe having means at one end 20 whereby it may be engaged over a tie, a cross piece attached to the opposite end of the shoe and adapted to extend across the head of the rail and parallel to the anchor, a compression spring disposed between that 25 end of the cross piece remote from the shoe and the corresponding end of the anchor, a lever mounted upon the shoe, a link pivotally connecting said lever to the end of

the anchor opposite the spring, and a runner upon which the forward end of the shoe and 30 the adjacent end of the cross piece is supported.

3. A tie spacer of the character described comprising an anchor having downwardly 35 extending lugs adapted to loosely embrace the head of a rail, the anchor extending out laterally from said lugs and at one end being depressed, a shoe having at one end a depending lug adapted to engage behind a tie, a cross piece upon which the other 40 end of the shoe is supported, said cross piece being adapted to extend across the head of the rail parallel to the anchor, a runner supporting said cross piece and the adjacent 45 end of the shoe, a bolt passing through that end of the cross piece remote from the shoe and through the adjacent end of the anchor, a spring surrounding the bolt and urging the cross piece and anchor apart, a lever pivoted upon the forward end of the shoe, and a link pivotally connected to the lever and to the adjacent end of the anchor. 50

In testimony whereof I hereunto affix my signature.

FRANCES M. NEWMAN.
